UNITED STATES PATENT OFFICE.

JOHN B. CROFOOT, OF ARLINGTON HEIGHTS, ILLINOIS.

STAPLER.

Application filed May 7, 1925. Serial No. 28,545.

My invention relates to a stapler and has for an object to provide a stapler having the body mounted on the base so as to be conveniently removed therefrom, and so arranged 5 that the body may be used in conjunction with the base as a stapler and may also be removed from the base and separably used as a tacker. Another object is to provide the stapler base with means for housing 10 staple strips therein. A further object is to provide a base with a removable drawer for receiving a staple container, and having means for frictionally retaining said drawer in position and also for readily removing 15 said staple container from said drawer. Another object is to provide a base having a stapler block with an inset of hardened metal removably mounted therein. A further object is to provide an improved 20 adjustable gage mechanism on the stapler. And another object is to provide a stapler having a body which has elements reversibly mounted thereon so as to adapt said body for use with the base as a stapler and using 25 the elements as stops, and said elements being arranged to be reversed and provide protruding claws to engage material for drawing and holding the same, thus adapting the 30 body to be used as a tacker apart from the base.

Other objects will appear hereinafter.

The invention consists in the combinations and arrangements of parts hereinafter described and claimed.

The invention will be best understood by reference to the accompanying drawings forming a part of this specification, and in which,

Fig. 1 is an elevational view, partly in section, showing the preferred form of my invention;

Fig. 2 is a horizontal sectional view, taken on line 2—2 of Fig. 1, showing the drawer and staple container in position in the base;

Fig. 3 is a view similar to Fig. 2, with the drawer and its contents removed;

Figs. 4 and 5 are vertical cross-sectional views, taken on lines 4—4 and 5—5 of Fig. 1;

Fig. 6 is an elevational view showing a modified form of stapler body mounted on the base in place of the body shown in Fig. 1;

Fig. 7 is a vertical cross-sectional view, taken on line 7—7 of Fig. 6;

Fig. 8 is an elevational side view of the body shown in Fig. 6, with the stop plates

reversed to adapt the body for use as a material puller and tacker;

Fig. 9 is an inverted plan view thereof, partly broken away; and

Fig. 10 is an elevational end view thereof.

The form of construction illustrated in Figs. 1 to 5 inclusive comprises a stapler body 12 removably mounted on a base 13 by means of a pair of lugs 14 on the base and a hand screw 15, with a knurled head 15', passing through said lugs and through a guide member 16 for guiding the staple strips in the body member 12.

The base is provided with a chamber 17 in which a drawer 18 is removably mounted and adapted to receive a container or cartridge 19 provided with staple strips 20, as best shown in Fig. 2. This drawer is provided with an opening 21 in the bottom to permit raising the container or cartridge 19 for convenient removal from the drawer.

Said drawer is also provided with shoulders 22 and 23 adjacent the inner end and the outer end respectively, for engaging the upper wall of the chamber 17, to aid in holding the drawer in position when fully within the chamber but to permit convenient removal when partly withdrawn from the chamber, and a spring 24 is further provided near the inner end of said chamber to

engage and press the drawer upwards and hold it frictionally in position with the shoulders 22 and 23 firmly engaging the top of the chamber while the drawer is in its closed position. The drawer is thus

firmly held in its closed position, but after it is slightly withdrawn so that the shoulders 23 are moved outside of the chamber then

it is more readily removable, and when it is sufficiently withdrawn to clear the spring 24 then it is very easily movable out of the chamber.

The base is provided with a stapler block 25 having a recess 26 in its upper end and an opening 27 leading from the recess into the chamber 17. An inset 28 of hardened steel and having notches 29 in its top, is mounted in the recess with a close fit, and is adapted

to be removed from the block, when said notches 29 are worn, by the use of a punch or similar article driven through the opening 27, the bottom 13' of the base 13 being

removably mounted on said base by the use of screws 13'' as indicated in Fig. 2, thus

providing access to said opening.

The gage mechanism provided on the form of invention shown in Figs. 1 to 5 includes a guide rod 30 provided with a head 31 which is firmly mounted with a screw or 5 the like in a seat provided by flanges 32 formed on the base, this guide rod and head being thus firmly held against movement with regard to the base. The gage means includes a pair of arms 33 and 34 which are 10 provided with openings or slots 33' and 34' for loosely engaging the guide rod 30; and a spring 35 is positioned between means on said arms for pressing said arms apart and to hold them clamped in position on the rod 15 30. Plates 36 and 37 are provided at the front of the arms to act as gages. The arms are readily slideable and adjustable on the rod by pressing their outer ends with the plates 36 and 37 toward each other.

20 The form illustrated in Figs. 6 to 10 inclusive is adapted for use as a stapler in conjunction with the base and is also adapted for use as a tacker when separated from the base, the same as in the preceding form, 25 when the hand screw 15 has been removed; but in this form the body is more particularly arranged to adapt it for use as a tacker and also to be used in drawing material like screens for tacking them upon the 30 frame bars, and the like. This form includes the base 13, with the gage mechanism used in the preceding form omitted herefrom. The body 40 is removably mounted on said base by means of the hand screw 15 35 passing through lugs 14 and through the staple guide member 16' of the body 40, and this body cooperates with the stapler block 25 when used as a stapler. The gage means in this form includes plates or members 41 40 adjustably mounted at each side of the body by the use of slots 42 engaging guide pins 43 provided on the body, and is firmly held in position by a screw 44 engaging through a slot 45. These slots are placed near one edge 45 of the plate so as to adapt the plates as gages when mounted in the manner shown in Fig. 6. The plates are also provided with claws or teeth 46 which are used to engage material as a screen or the like for drawing 50 and holding the material into position on the screen bar or the like when the device is used as a tacker. The screen or similar material may thus be drawn in position on the frame bars or the like, by using only the body 40, and by depressing the plunger in 55

the usual manner the staple is driven in position through the screen or material into the frame.

It is apparent from the above disclosure that either form of body may be used with 60 the base when employed as a stapler, and may be used by itself when employed as a tacker, and that the form of body shown in Figs. 6 to 10 is more especially adapted for use as a tacker and to draw the material 65 into position upon a frame or the like and to hold it in such position by use of the teeth 46, during the tacking operation.

While I have illustrated and described the preferred form of construction for carrying 70 my invention into effect, this is capable of variation and modification without departure from the spirit of the invention. I, therefore, do not wish to be limited to the precise details of construction set forth, but 75 desire to avail myself of such variations and modifications as come within the scope of the appended claims.

Having described my invention what I claim as new and desire to secure by Letters 80 Patent is:

1. In a stapler, a gage mechanism including a guide member, a pair of arms slideable on said guide member and also slideable relatively to each other, and a spring forcing 85 said arms apart to clamp said guide member.

2. A stapler comprising a guide rod, a pair of arms slideable on said rod, a spring arranged between said arms to force said arms apart and thus clamp said rod, and a 90 gage plate on said arms cooperating with said stapler to position work therein.

3. In a stapler, a base having a flanged seat, and gage mechanism including a guide member with a head firmly but removably 95 mounted in said flanged seat, and gage means adjustably mounted on said member.

4. In a stapler, a base, a guide rod on said base, and gage means including a pair of arms and a spring for adjustably clamping 100 and holding the arms in position on said rod.

5. In a stapler, a base, a guide rod on said base, and gage means including arms having gage plates at the front and having openings wherein said rod engages and also 105 having spring means to clamp said arms in position on said rod.

In testimony whereof I have signed my name to this specification.

JOHN B. CROFOOT.
